CLAIM

The ornamental design for an indoor wall with built-in home appliances, as shown and described.

DESCRIPTION

FIG. 1 is a front perspective view of the indoor wall with built-in home appliances showing our new design;

FIG. 2 is a front view thereof;

FIG. 3 is a rear view thereof;

FIG. 4 is a left side view thereof where the right side view is a mirror image;

FIG. 5 is a top view thereof;

FIG. 6 is a bottom view thereof;

FIG. 7 is a front perspective view in a condition that the drawer at the front bottom has been opened and the projector has been exposed;

FIG. 8 is a front view of FIG. 7;

FIG. 9 is a rear view of FIG. 7;

FIG. 10 is a left side view of FIG. 7 where the right view is a mirror image;

FIG. 11 is a top view of FIG. 7;

FIG. 12 is a bottom view of FIG. 7; and,

FIG. 13 is a reference view showing the use state that the front part of the claimed design is used as a screen by operating the projector.

The dash-dash broken lines in FIG. 13 of an image on the screen depict environment that forms no part of the claimed design. The remaining dash-dash broken lines in the figures depict portions of the indoor wall with built-in home appliances that form no part of the claimed design. The dash-dot broken lines define the bounds of the claimed design and form no part thereof.
